UNITED STATES PATENT OFFICE.

JOHN JAMES, OF FORT ATKINSON, WISCONSIN, ASSIGNOR TO THE JAMES MANUFACTURING COMPANY, OF FORT ATKINSON, WISCONSIN.

STANCHION.

1,211,586.

Specification of Letters Patent. Patented Jan. 9, 1917.

Application filed August 18, 1913. Serial No. 785,194.

To all whom it may concern:

Be it known that I, JOHN JAMES, a citizen of the United States, residing at Fort Atkinson, county of Jefferson, and State of Wisconsin, have invented new and useful Improvements in Stanchions, of which the following is a specification.

My invention relates to improvements in cattle stanchions and it pertains more especially, among other things, to the device for locking and retaining the inclinable standard of a pair of stanchions in its closed or vertical position in connection with the stationary standard.

The object of my invention is to provide simple, inexpensive and durable mechanism for locking a pair of stanchion bars in closed or animal retaining position. The inclinable bar being adapted to be swung to closed position and automatically locked during the final movement to closed position.

My invention is explained by reference to the accompanying drawings in which,

Figure 1 represents a plan view thereof, and Fig. 2 is a side view.

Like parts are identified by the same reference numerals in both views.

The stanchion bars may be of ordinary construction except at the top where my improved locking device is located, the drawings therefore only show the inturned upper end portions of the stanchion bars together with the locking mechanism.

1 is the upper end of the relatively stationary stanchion bar and 2 represents the upper end of the inclinable stanchion bar. The lower ends of the bars 1 and 2 are adapted to be connected with the lower stanchion supporting frame in any convenient manner, while the upper end of such stanchion is also adapted to be connected with the upper frame member in any convenient manner and invention herein be predicated more especially upon the means of locking the upper end of the inclinable stanchion bar 2 to the stationary stanchion bar 1 and the mechanism for releasing the upper end of the inclinable stanchion bar. The stationary stanchion bar 1 is provided with a latch or locking member 3 which is pivotally connected therewith through the angular shaft 4 and the member 3 is normally thrown down into the locking position shown in Fig. 2 by the recoil of the springs 5. The springs 5 are connected at one end with the

member 3 through the members 6 and at their opposite ends with the member 1 through the bolt 7. The member 2 is T-shaped in cross section, comprising a horizontal member 8 and a vertical flange 9. The vertical flange 9 is provided with a recess 10 for reception of the latch or locking member 3.

11, 12 are curved fingers which are formed integral or rigidly connected with the member 1 and they are adapted to serve as guides to the stanchion bar 2 as the same is brought into locking engagement with the stanchion bar 1. The upper face of the flange 9 at the inner end 12 of the inturned portion of the stanchion bar 2 inclines downwardly, preferably along a curved line, whereby when the inclinable bar 2 is swung inwardly to its closed or animal retaining position the downwardly inclined portion 12 of the flange 9 passes underneath the U-shaped locking member 3, whereby the locking member 3 is raised and caused to slide over and upon the inclined surface 13 of said standard 2 until it reaches the recess 10, when said member 3 is thrown down into said recess 10 with a quick positive movement by the recoil of the springs 5, whereby the standard 2 is retained in its locked or vertical position.

The locking member 3 is provided with an angular aperture 14 for the reception of the angular shaft 4 and said locking member is raised and brought out of locking engagement with the member 2 simply by turning said shaft in its supporting bearings. As a means of turning the shaft 4, I preferably provide the same with hand wheels 15, whereby as either one of said hand wheels 15 is turned a partial revolution, said locking member 3 will be brought out of said recess 10, whereby the standard 2 will be released and may be thrown back preparatory to admitting the head and neck of the animal between the respective standards. While the locking member 3 may be actuated and brought to its locking position with a single spring 5, I preferably provide two springs 5 as more clearly shown in Fig. 1, whereby said member 3 is brought to its locking position by the coöperation of both of said springs.

It will be understood, that while I have shown and described the locking member as being actuated by two springs, I do not wish

to limit or confine my device to said springs as said locking member may be actuated by other forms of springs and the spiral springs dispensed with. I wish it also to be understood that while I have shown hand wheels 15 in connection with the respective ends of the shaft 4 for disengaging the locking member 3, one of said wheels may, if desired, be dispensed with or either one or both 10 of said wheels may be substituted by an actuating handle or lever. The form shown, however, is preferred as the stanchions may be readily unlocked from either their front or rear sides by simply turning one of said hand wheels.

Having thus described my invention, what I claim as new and desire to secure by Letters Patent is,

1. The combination of a stationary and 20 inclinable stanchion bar, each provided with converging upper end portions, a transverse operating shaft pivoted to one of said upper end portions and provided with an operating handle, a U-shaped latch member mounted upon said shaft and held against rotation thereon, a spring connecting said latch member below the shaft with the latch supporting stanchion bar, said spring having tension to draw the latch downwardly, and a 25 flange carried by the converging portion of the other stanchion bar and provided with

a notch in which said latch may engage, the upper margin of said flange having a downwardly tapering inclination at its inner end, whereby it may pass underneath the latch 31 and lift the same in position for engagement with said notch with the side arms of the latch on opposite sides of said flange.

2. In a device of the described class, the combination of a pair of stanchions, a revoluble shaft supported from and arranged transversely to the upper ends of one of said stanchions, handles rigidly affixed to the protruding ends of said shaft, a U-shaped latch centrally affixed to said shaft between 45 said handles, a pair of springs for normally retaining the front end of said latch in its locked position, whereby said latch is caused to engage said inclinable stanchion when brought to its vertical position, said handles being adapted to enable a person to revolve 50 said shaft and disengage said latch from the inclinable member of said stanchion, from either the front or rear side of said stanchions, all substantially as and for the purpose specified.

In testimony whereof I affix my signature in the presence of two witnesses:

JOHN JAMES.
